UNITED STATES PATENT OFFICE.

JOSEPH HASKINS, OF CATLIN, ILLINOIS.

GENERATOR.

1,088,020.

Specification of Letters Patent. Patented Feb. 24, 1914.

Application filed December 6, 1911. Serial No. 664,208.

To all whom it may concern:

Be it known that I, JOSEPH HASKINS, a citizen of the United States, residing at Catlin, in the county of Vermilion and State of Illinois, have invented a certain new and useful Improvement in Generators, of which the following is a specification.

My invention relates to improvements in generators preferably for use in connection with calcium carbide and water to generate acetylene gas.

It is illustrated diagrammatically in one form of the accompanying drawing, wherein—

Figure 1 is an elevation; Fig. 2 is a vertical section; Fig. 3 a detailed elevation; Fig. 4 a detail.

Like parts are indicated by like letters in all the figures.

The annular base A is provided about its outer edge with the upwardly extending collar A¹ from which projects outwardly the horizontally disposed flange A², and is provided with the centrally disposed inverted cup A³ in which is mounted the flanged tube A⁴. The collar A⁵, rigidly mounted on the tube A⁴ within the cup A³, carries the reservoir A⁶, having adjacent its top the discharge ports A⁷. The tube A⁴ terminates at its lower end in the conical nozzle A⁸, having the passage A⁹ discharging into the cup A³ adjacent its base.

The cylindrical housing B, closed at one end by the cover B¹, is rigidly mounted on the base A and surrounded at its base by the collar A¹ forming the liquid reservoir B² which may be filled through the port B³ in the cover B¹ closed by the filler cap B⁴. The sleeve B⁵ is fixed in position centrally in the cover B¹ and contains the sleeve B⁶ screw threaded therein. The shaft B⁷ screw threaded in the sleeve B⁶ terminates at one end in the thumb screw B⁸ and at the other in the needle valve B⁹ in opposition to the conical valve seat B¹⁰ in the tube A⁴. The gas or generating pot or chamber C, provided with the closed bottom C¹ and the annular flange C² about the open top is in slidable engagement with the collar A¹ and is provided with the lug C³ in opposition to the inclined holding hook C⁴ projecting from the flange A². The packing C⁵ is compressed between the flanges C² A² when the pot C is rotated to cause the lug C³ to ride up on the inclined hook C⁴. The pot C is provided with the inwardly extending an-

nular ridge or shoulder C⁶ intermediate its two ends and slightly below the base A. The ring C⁷, having the downwardly extending collar C⁸ carries the basket C⁹ and rests upon the shoulder C⁶. Carbid or other gas forming substance C¹⁰ is contained within the basket C⁹.

The gas cleaning chamber D is located within the reservoir B² and separated therefrom by the wall D¹ and communicates by means of the port D² through the base A with the interior of the pot C. The porous strainer D³ of felt or other suitable substance is located in the port D² and extends 60 partially within the chamber D and partially within the pot C. The pipe D⁴ extends outwardly from the chamber D through the wall of the housing B, and is closed at its outer end by the cap D⁵ having the burner 65 hole D⁶ through which the gas to be consumed escapes. The housing B carries the hook or handle E whereby the lamp may be supported or carried.

It will be evident that while I have shown 80 in my drawing an operative device, still many changes might be made in size, shape and arrangement of parts without departing materially from the spirit of my invention. I wish, therefore, that my drawing be regarded as in a sense diagrammatic.

The use and operation of my invention are as follows: The upper cylindrical housing is first filled with water or other suitable liquid and the needle valve closed by rotating the valve rod until the needle point sits firmly upon the conical seat. The removable basket in the lower pot is then filled with calcium carbide or any other suitable material and is dropped into the pot. It 90 will be observed that when in this position there is an air space all around the basket and the contents nowhere come in contact with the pot. The pot is then slipped up over the base of the reservoir and rotated 100 until the lugs thereon ride up over the hooks on the reservoir, drawing the two tightly together, compressing the packing material between the flanges on the pot and reservoir respectively. The lamp is then ready for 105 operation. The needle valve is slightly opened and the liquid or water allowed to flow from the reservoir through the discharge nozzle into the suspended cup. It fills this cup and overflows from the top 110 through the overflow ports, travels down the side of the cup and drips into the carbide in

the basket. The action of the water and the carbid forms acetylene gas, which fills the pot and passes through the port, being purified by the porous strainer, into the gas chamber and thence out through the pipe to a nozzle or any other suitable burner.

It will be evident that the immersion of the drip nozzle into a cup forms a water seal or trap and prevents the return of any 10 of the acetylene through the needle valve into the water reservoir. It will also be noticed that the comparatively fine needle valve and nozzle are protected from the carbid and the only openings exposed to the carbid are the comparatively large drip passages or ports in the top of the cup, and these ports, since they are located a considerable distance away from the carbid, are protected themselves from it, and thus the 15 danger of the stopping up of the water passages and the cutting off of the water supply by the powdered consumed carbid is entirely disposed of. The use of the basket within the pot forms a more convenient 20 cleansing of it and permits free circulation of the gas about the carbid. And, moreover, since the basket and its contents are out of contact with the pot, there is less danger of heating of the pot and reservoir by the heat 25 formed when the gas is generated. The use of a removable basket prevents the packing of the moistened and consumed carbid in the bottom of the reservoir, and thus permits 30 convenient and effective cleansing of the generator chamber. Moreover, since the carbid mass is open at all points thereabout, it 35 may more evenly be consumed, and will discharge its gas in a more even and regular manner than it otherwise would. It will be 40 observed also that the water supply pipes

and nozzle are all located out of contact with the carbid, and therefore any deleterious action on the metal which the carbid itself might have is limited entirely to the cup and easily removable basket, and the more delicate or more expensive portions of the apparatus are completely out of contact therewith and come in contact only with the gas 45 itself.

I claim:

1. A generator comprising a liquid reservoir, a cylindrical pocket upwardly projecting from the lower wall of said reservoir and separated from the liquid-containing portion thereof and open at its bottom, a supply pipe projecting downwardly from the upper wall of said pocket, a liquid-containing trap or cup mounted on said supply pipe located within and surrounded by said pocket and a carbid-containing housing 55 mounted on said liquid reservoir and of such size as to be substantially completely filled by the carbid.

2. A generator comprising a liquid-containing reservoir, a carbid-containing chamber immediately adjacent thereto and of sufficient size only to contain sufficient carbid for a charge, a horizontal wall separating the liquid-containing reservoir and the carbid chamber, an upwardly extending boss in said wall, a liquid-containing trap or cup in said boss, a discharge from the upper portion of such cup said discharge being located in and protected by said boss and a liquid supply from the reservoir to the bottom of the cup.

JOSEPH HASKINS.
